UNITED STATES PATENT OFFICE.

BERNHARD BEHR, OF DRESDEN, GERMANY.

SIGNALING DEVICE FOR CALCULATING-MACHINES.

1,105,396.

Specification of Letters Patent. Patented July 28, 1914.

Application filed December 16, 1912. Serial No. 737,008.

To all whom it may concern:

Be it known that I, BERNHARD BEHR, a subject of the Kingdom of Saxony, in the German Empire, residing at 19 Hamburgerstrasse, Dresden, Germany, have invented certain new and useful Improvements in Signaling Devices for Calculating-Machines, of which the following is a specification.

My invention relates to signaling devices for indicating when the capacity of Thomas calculating machines is exceeded.

In Thomas calculating machines, as for instance disclosed by Patent No. 1,034,756, it was heretofore a disadvantage that the gong for indicating when the capacity of the machine was exceeded did not always sound in all positions of the ruler because the gong had to be located at that place outside the ruler where the tens were no longer transferred. Accordingly, behind the last device for transferring tens, instead of the transferring lever proper a suitably shaped two-armed lever has heretofore been arranged whose motion was imparted to the gong. There are, however, a number of positions of the ruler in which the lever connected with the outside numeral wheels no longer comes into engagement with the mechanism for sounding the gong, so that the gong is not sounded. In these cases in which it is no longer indicated when the capacity of the machine is exceeded, the person calculating must pay very careful attention in order to avoid incorrect results and in order not to turn the handle beyond the capacity of the machine.

A primary object of my invention is to provide that whenever the capacity of the machine is exceeded the same shall be indicated in every position of the ruler. To this end I cause the numeral wheel located behind the last device for transferring tens during its movement from the cipher nine to zero to actuate a stop mechanism which moves either directly or by means of an intermediate mechanism a further stop member whose length is equal to the distance through which the ruler is displaced. This intermediate stop may be a mechanical member, such as a rocking frame of the length of the said distance for example, which, when the capacity of the machine is exceeded, is indirectly moved by the rotation of the numeral wheel and imparts its motion to the mechanical actuating mechanism of the gong. The intermediate stop may, how-

ever, operate electrically, when the stop or the intermediate member of the numeral wheel located behind the last device for transferring tens closes a contact device in 60 an electric circuit comprising an electric bell, the bell being arranged in the fixed part of the machine.

Three illustrative embodiments of my invention as applied to a Thomas calculating 65 machine of the customary construction are represented by way of example in the accompanying drawings, wherein:—

Figures 1 and 2 are plan views showing a Thomas calculating machine of the usual 70 construction having the ruler located in its normal position, and shifted to the right one place, respectively; Fig. 3 shows a plan of the invention, the cover plate of the machine and of the ruler being broken away, Fig. 4 75 is a side elevation of the device shown in Fig. 3, Fig. 5 is a detail view of the rocking frame shown in Figs. 3 and 4. Fig. 6 is a plan view of a modified form of my invention. Fig. 7 is a cross-section through the 80 same, and Fig. 8 is a sectional detailed view of the contact forming elements.

Referring to the drawing, Fig. 1 shows a form of the machine customary heretofore with the ruler in its normal position. When 85 the ruler is in this position and the capacity of the machine is exceeded, the gong which is located behind the thirteenth numeral wheel is struck. When the ruler occupies the position shown in Fig. 2, on the contrary, 90 when the numeral wheels show nine, the capacity of the machine will be exceeded if more additions are made; in this position of the ruler, however, the going is not sounded. According to the present invention this 95 disadvantage is met by the numeral wheel located behind the last device for transferring tens actuating by a stop either directly or by means of an intermediate mechanism a further stop member which is of the length 100 of the movement of the ruler and is fastened to a fixed part of the machine. The movement of this stop member is made use of for sounding the gong arranged in the fixed part of the machine. At the rear side of the machine (Fig. 3) there is arranged a frame 11 so as to turn around the axis 15, the frame 14 consisting of the vertical strips 17 and being moved under the action of a spring 45 in the direction of the arrow 16. This frame 105 comprises the vertical strips or bars 17 whose lower ends are fast on the shaft 15

and whose upper ends carry a longitudinal bar 11. The rod 19 is pivoted to the frame at 18 and is connected at 20 with the tens tappet 21. The elastic rod 22 is pivotally connected with the rod 19 and carries the hammer head 12 which strikes against the gong 13 whenever the frame 14 is rocked. The frame 14 is connected with the tappet 21 in such manner that when the frame is moved, the tens tappet is moved exactly as if the same were rocked by the cutting finger 23 of the numeral wheel 1 when passing from nine to zero. The spring influenced pin 25, whose front end is beveled, and whose rear end bears against the upper bar of the frame 14, is located below the cover plate of the ruler 4. The finger 23 of the outermost numeral wheel 1 is lengthened beyond the pivot 26 in the form of a tooth 24 which, as soon as the numeral wheel rotates from nine to zero, abuts against the pin 25 and thereby rocks the frame 14, whereby the gong 13 is sounded. As the pin 25 is carried by the ruler, the frame 14 is moved in every position of the ruler; consequently the gong sounds whenever the capacity is exceeded without regard to the position of the ruler.

In the machine according to Fig. 3 the gong is located behind the last numeral wheel because it is assumed that the machine calculates to the last place. In machines which do not calculate through, *i. e.* in those whose last places, *e. g.* the thirteenth to the sixteenth, do not possess devices for transferring the tens, the gong must be located directly behind the last tens transference device thus at the thirteenth place.

The modified form of my invention represented in Figs. 3 to 5 shows a mechanical transfer which of course can be substituted by an electric one. The electrical transfer may be constructed in different ways, for instance as shown in Figs. 6 to 8. As shown in said figures the mechanical transfer is replaced by an electrically operated one. At a fixed part of the machine an electrically operable gong is arranged and a metal bar is located within the circuit in which said 50 gong is situated, said metal bar having a length equal to the extent of movement of the ruler. The arrangement of these parts is such that the gong is sounded when the numeral wheel after the last transfer of the 55 tens in moving from nine to zero and closes a circuit for operating the gong. Any well known means may be employed for closing said circuit, as for instance a contact spring or a contact brush upon a spring controlled 60 lever, etc. Preferably spring pistons are used which do not require frequent repairs but remain continuously in good working order. The casing of the machine can be used as the return conductor. Upon the under-side of the return numeral wheels are

arranged in the well known manner and the wheel 1 located behind the last device for transferring the tens is arranged upon a shaft 26. Simultaneously with the numeral wheel a tooth 24 is operated which engages a bolt 27 standing under the tension of a spring and actuates the same. The bolt 27 is guided within a bushing 28 in which a spring 29 is located and which bushing is closed at the top by a nut 30 or the like. The bushing 28 is suitably secured to a web 33 or the like arranged at the under-side of the ruler 4. The bolt or pin 27 under the influence of the spring 29 tends at all times to move toward the shaft 26 of the numeral wheel 1. The bolt 27 as shown in Fig. 8 carries a spring controlled piston which makes contact with the contact rail 34 secured to the casing of the machine. For this purpose the bolt 27 is provided with shoulders carrying a sleeve 31 which guides a push button 32 which in the well known manner is constantly pressed by a spring toward the outside. The piston is of a length which prevents it during the normal position of the bolt 27 to contact with the rail 34. This rail 34 as mentioned above is of a length equal to the extent of the movement of the ruler and is secured by means of angle pieces 35 of insulating material to a partition or web 36 within the casting 37. By means of a metal bar, a wire or the like, 38 the contact rail 34 is connected with the binding post 39 of a gong 40, the other binding post 41 of which is connected to the pole 42 of a source of electricity 43. The other pole of said source is conductively connected to the casing by means of a screw 44, however said latter pole being properly insulated may just as well be connected to the bolt 27 or its guiding parts 28, 30 and 33 or also to a finger 24 which then must be properly insulated. As shown in Fig. 8 a spring controlled piston 31, 32 is employed for making contact with the rail 34. This piston naturally can just as well be replaced by a U-shaped contact spring or a contact brush which is secured to a spring controlled lever.

The device operates as follows: As soon as the piston 32 is contacting with the insulated contact rail 34 the circuit will be closed and the gong 13 of the alarm device 40 will be sounded. It will be clear that other means may be employed in place of the contact rail 34, thus for instance the contact rail may be replaced by a flexible conductor guided upon the ruler to a contact piece with which the spring controlled pistons 31, 32, or any other well known suitable means may contact. The other end of said flexible conductor is secured to a fixed part of the machine or can be for instance connected to the metal bar 38.

I do claim:—
1. In a calculating machine of the char-

acter described, the combination with the frame and a ruler slideable thereon, numeral wheels mounted in a row on the ruler and tens transference devices on the ruler for 5 transferring the tens from one numeral wheel to another, of a gong, means for sounding the gong and means for causing the ruler in any of its positions to sound said gong when the capacity of the machine is reached.

10 2. In a calculating machine of the character described, the combination with the frame and a ruler slideable thereon, numeral wheels mounted in a row on the ruler and tens transference devices on the ruler for 15 transferring the tens from one numeral wheel to another, of a gong, means for sounding the gong, said means comprising a bar of a length equal to the distance through which the ruler can be displaced on the frame, and a member carried by the ruler and adapted to be actuated by the last numeral wheel and to coact with said bar and thereby sound the gong when the capacity of the machine is exceeded.

20 3. In a calculating machine of the character described, the combination with the frame and a ruler slideable thereon, numeral wheels mounted in a row on the ruler and tens transference devices on the ruler for 25 transferring the tens from one numeral wheel to another, of a gong mounted in the frame, means for sounding the gong, said means comprising a bar of a length equal to the distance through which the ruler can be displaced on the frame, said bar being mounted to rock in the frame, a cutting finger, carrying a tooth, mounted on the pivot of the last numeral wheel, and a pin mounted on the ruler and adapted to be driven by the said tooth and rock said bar and thereby sound the gong when the capacity of the machine is exceeded.

30 4. In a calculating machine of the character described, the combination with the frame and a ruler slideable thereon, numeral wheels mounted in a row on the ruler and tens transference devices on the ruler for 35 transferring the tens from one numeral wheel to another, of a gong mounted in the frame, means for sounding the gong, said means comprising a bar of a length equal to the distance through which the ruler can be displaced on the frame, said bar being mounted to rock in the frame, and a member carried by the ruler and adapted to be actuated by the last numeral wheel and to coact with said bar and thereby sound the gong when the capacity of the machine is 40 exceeded.

4. In a calculating machine of the character described, the combination with the frame and a ruler slideable thereon, numeral wheels mounted in a row on the ruler and tens transference devices on the ruler for 45 transferring the tens from one numeral wheel to another, of a gong mounted in the frame, means for sounding the gong, said means comprising a bar of a length equal to the distance through which the ruler can be displaced on the frame, said bar being mounted to rock in the frame, a cutting finger, carrying a tooth, mounted on the pivot of the last numeral wheel, and a pin mounted on the ruler and adapted to be driven by the said tooth and rock said bar and thereby sound the gong when the capacity of the machine is exceeded.

50 In testimony whereof I have hereunto set 55 my hand in presence of two subscribing witnesses.
